J. J. SHOEMAKER.

TOWEL HANGER.

APPLICATION FILED SEPT. 5, 1919.

Patented Feb. 24, 1920.

UNITED STATES PATENT OFFICE.

JEREMIAH J. SHOEMAKER, OF AKRON, OHIO.

TOWEL-HANGER.

1,331,589.

Specification of Letters Patent. Patented Feb. 24, 1920.

Application filed September 5, 1919. Serial No. 321,866.

To all whom it may concern:

Be it known that I, JEREMIAH J. SHOEMAKER, a citizen of the United States, residing at Akron, in the county of Summit and 5 State of Ohio, have invented a new and Improved Towel-Hanger, of which the following is a specification.

This invention has reference to that class 10 of towel hangers by which the towel is hung or suspended from the holder devices along its upper edge in such manner, whereby the ordinary towel may be held in position for convenient use.

The primary object of my invention is to 15 produce an appliance of the general character stated of a very simple and inexpensive construction and with the parts so arranged and combined whereby to maintain them from being easily disconnected or put out 20 of the desired condition and on which the towel may be held in position for use and easily and quickly removed, when desired.

Another object of my invention is to provide a towel holder that includes a hanger 25 portion composed of a piece of stout wire adapted for being readily sustained from an overhead support and a body member also composed of a spring wire strand that is bent to the desired shape and is adapted 30 for being swivelly sustained on the hanger member so that it may be conveniently turned around to provide for using either side of the towel, the said body portion also including resilient portions, near each end, 35 with which the upper edge of the towel may be readily engaged, the said resilient portion being arranged to provide for hanging different sizes of the ordinary towel.

With other objects in view, that will hereinafter be apparent, my invention embodies, 40 in a towel holder, the peculiar features of construction and arrangement of parts as set out in the following detailed description, as specifically stated in the appended claims 45 and illustrated in the accompanying drawings, in which:

Figure 1 is a perspective view of my towel holder, the same being shown as applied for use.

50 Figs. 2 and 3 are diagrammatic views thereof that illustrate how the different sizes of towels may be supported therefrom.

Fig. 4 is a cross section, partly in elevation, taken substantially on the line 2—2 55 on Fig. 1.

Fig. 5 is a detail perspective view of the hanger or central support.

Fig. 6 is a like view of one of the towel edge resilient clamping members.

Fig. 7 is a similar view and illustrates a 60 double or endless towel connected with the clamping member.

In carrying out my invention, I provide a hanger that consists of a stout wire strand 1, the upper end of which is bent into an 65 open mouthed loop 10 which provides for readily supporting the hanger from an overhead cross wire, hook, or other like support.

The body portion 2 of my towel hanger is also composed of a resilient wire strand, 70 preferably galvanized wire, which midway its length is bent to form an eye 20 that constitutes a lower bearing or engaging the lower end of the hanger 1, as shown.

Midway thereof, each end portion of the 75 body wire 2 is bent upon itself to form elongated horizontal clamping loops 21—21, the shanks of which are restricted by the straight members 22 that lie closely against adjacent portions of the main or body 80 wire 2.

At the shank portions of each of the resilient clamping loops, the free ends of the wire 2 are coiled, one or more times, about the main end portions of the said body wire 85 2 as at 23 and from thence the said free ends of the wire extend diagonally inwardly toward each other with their terminals twisted into eyes 24—24 for engaging the upper end of the hanger 1, above a collar 1^a twisted 90 90 therein, the said eyes 24 constituting the upper swivel bearings for the body portion 2, as shown.

In the practical assemblage of the parts, the lower end of the hanger 1, after the body 95 portion 2 is fitted thereon, is turned into a horizontal coil which constitutes a bottom stop or keeper 25 for holding the body portion on the hanger.

The diagonally inwardly extended members constitute braces for holding the body portion in rigid relation when sustained on the upper end.

One of the advantageous features in my 105 construction of towel hanger is that different sizes of the ordinary towel may be hung thereon, since all that is necessary is to twist portions of the upper edge of the towel and slip them into clamping connection with the clamping loops, see Fig. 3.

By forming the body portion in the manner described and swivelly suspending it on the hanger 1, as stated and shown, the hanger, with the towel, may be freely turned 5 around so that either side of the towel may be used, and since the upper twisted ends 24—24 of the diagonally extended portions of the body wire 2 rest upon the top of the twisted collar 1^a, the weight of the towel 10 will not collapse the rack.

At the lower end, just above the bottom rest or stop member 25, the hanger 1 is flattened as at 25^a, which portion tends to hold the lower bearing eye 20 from slipping up 15 or flexing along the standard 1 and also for firmly holding the said eye connection 20 between the part 25^a and the member 25.

While I have stated that my appliance is particularly adapted for hanging the usual 20 one piece towel, it is obvious that an endless towel may likewise be supported by making the device of a suitable size to permit of connecting one of the loop ends of the double towel, as indicated in Fig. 7.

25 In my construction of towel holder, the towel may be readily attached to or removed from the device without danger of tearing the towel or injuring the holder, the shank portions of the clamping loops affording sufficient tension for holding the 30 towel suspended and against being readily pulled away from the holder.

What I claim is:

1. A towel holder comprising a hanger

adapted for being suspended from an overhead support, and a body portion bent up 35 from a spring wire strand, said body having a pair of horizontally disposed eyes midway the ends thereof, said eyes being adapted for swivelly engaging the hanger, whereby 40 the holder may be rotated in the horizontal plane about the hanger, the latter including means for holding the body from displacement endwise of the hanger, each end of the body having a bent up loop for 45 receiving and clamping portions of the upper edge of the towel.

2. As a new article, a towel holder comprising a hanger that consists of a spring wire, one end of which is bent to constitute 50 a hook and a horizontal keeper at the base of the hook portion, the lower end being horizontally bent to constitute a bottom stop, a body portion that consists of a single spring wire strand and which includes a 55 horizontal bottom member, each end of which is bent to form an elongated loop having a restricted neck, the said horizontal member being also bent to form an eye for swivelly engaging the lower end of the 60 hanger, the free ends of the said wire being bent diagonally upward toward each other and each terminating in an eye, the said eyes constituting bearings for swivelly engaging the upper end of the hanger at a point above 65 the upper keeper portion thereof.

JEREMIAH J. SHOEMAKER.
